UNITED STATES PATENT OFFICE.

GEORGE H. HASLOP, OF WORCESTER, MASSACHUSETTS, ASSIGNOR OF ONE-HALF TO HENRY E. WHITCOMB, OF WORCESTER, MASSACHUSETTS.

ENVELOP-MACHINE.

SPECIFICATION forming part of Letters Patent No. 721,701, dated March 3, 1903.

Application filed October 16, 1902. Serial No. 127,520. (No model.)

To all whom it may concern:

Be it known that I, GEORGE H. HASLOP, a citizen of the United States, residing at Worcester, in the county of Worcester and State of Massachusetts, have invented a new and useful Envelop-Machine; of which the following is a specification.

The object of this invention is to improve that class of envelop-machines in which the folding-bed moves up and down vertically and in which the envelop is pushed off of the folding-bed when it is in its lowest position. An example of this style of machine is shown in patent to Smythe, No. 191,575, granted June 22, 1869. In developing a machine of this character to run at a high speed it has been found necessary to provide a very accurate guiding means for the vertically-moving folding-bed and means whereby the envelop can be accurately and positively ejected off of the folding-bed. To accomplish these ends, I provide a guide-support for the folding-bed which has a dovetailed groove cut therein. The folding-bed is provided with a dovetailed tenon engaging said groove, and a tapered gib is interposed between the tenon and the guide, so that the parts can be very accurately adjusted and all wear taken up. A stopping-piece is secured to the bottom of the tenon to accurately define and determine the upper position of the bed when it receives the envelop. It has been customary heretofore in devices of this kind either to have the pusher-fingers move across the face of the bed or across the bed in slots cut therein. The first of these devices has been found to be objectionable, because the slightest derangement of the parts or any inaccuracy will cause the pusher-fingers to ride over the envelop or the envelops to stick between the pushers and the top surface of the bed, clogging the machine and tearing the envelops. The other of these devices has been found objectionable, as the slots in the bed are apt to mar or bruise the envelop. To overcome this objection, I provide a mechanism which as the folding-bed drops down will slightly separate the rear edge of the envelop from the surface of the bed, and I preferably make the ends of the pusher-arms V-shaped, so

that they will engage the relatively elevated rear edge of the envelop and push the envelop accurately off of the folding-bed. This overcomes the objection previously noted and still leaves the surface of the folding-bed smooth, so as not to mar the envelop. 55

The invention further consists of certain details of construction hereinafter pointed out, and defined in the claims.

Referring now to the accompanying three 60 sheets of drawings, I will describe the best form now known to me for practicing the invention.

In the drawings, Figure 1 is a sectional elevation of enough of the mechanism to illustrate the operation. Fig. 2 is a similar view of the bed in its lowered position as compared with the raised position shown in Fig. 1. Fig. 3 is a plan view of the support and folding-bed. Fig. 4 is a front view of these parts. 70 Fig. 5 is a rear view of these parts; and Fig. 6 is a perspective view, on an enlarged scale, illustrating a detail.

Referring to the drawings and in detail, A designates the table. 75

B designates the guide-support, having a flange B', which is bolted to the under side of the table. A dovetail groove C is cut in the guide-support.

D designates the folding-bed, made in the 80 form of an inverted L and having ribs D' between its two sides. A dovetail tenon E projects from the folding-bed D. The folding-bed is arranged in an aperture cut in the table, as shown. The folding-bed is surrounded by the usual four folders, two of which, F F, are shown. These folders are arranged slightly below the level of the table A. One side of the dovetail tenon is cut on an incline 10, as shown. A tapered 90 gib 11 is arranged between this inclined side and the corresponding side of the dovetail groove C. This gib is provided with a slotted shoulder 12, engaging which is the head of a screw 13 and collar 14, secured thereon. 95 The screw is tapped into the tenon E, and by adjusting the screw the tenon can be very accurately fitted to the groove, so that the bed will have an accurate movement and so that the parts can be adjusted for wear. A stop- 100

piece 15 is secured to the bottom of the tenon by screws 16 and is arranged to strike on the bottom of the guide-support B to define the upper position of the bed. Separated pins 18 18 are fitted in small holes cut in the bed D and in small brackets or projections extending from the upright side of the folding-bed. Each of these separated pins has a spring 19 thereon engaging a pin 20 inserted in the separated pins. A connecting-piece 21 connects the ends of the separated pins 18. An arm 22, secured to a support 23, engages this connecting-piece. When the bed is in its lifted position, as shown in Fig. 1, the ends of these pins will be below the top surface of the folding-bed; but when the folding-bed is reciprocated down to its lowest position, as shown in Fig. 2, the ends of the separated pins will project slightly up above the surface of the folding-bed and will separate the rear edge of the envelop from the surface of the folding-bed.

The folding-bed is reciprocated by the following means: A slot 24 is cut in the guide-support B. A stud 25 is secured in the upright side of the folding-bed. A link 26 engages this stud and a pivoted arm 27, which carries a roll 28, engaging a cam 29, arranged on the operating-shaft of the machine. A spring 30 is arranged to hold the roll 28 in engagement with the cam.

31 designates the pusher-arms. The ends of these pusher-arms are V-shaped or notched, as at 32, for the purpose mentioned. These 35 pusher-arms work in slots cut in the table and are arranged in position outside of the lifting-pins to move across the top surface of the folding-bed when the same is in lowered position.

40 The rear folder is slotted in the usual manner to allow the pusher-arms to pass forward under the same. The pusher-arms are connected by a piece 33, which connects by link 34 to a pivoted lever 35, which connects by link 36 to a pivoted arm 37, having a roll 38, engaging a cam 39, secured on the operating-shaft of the machine. A spring 40 is used to keep the roll 38 on its cam.

The parts are timed to operate as before described, and by the improved constructions herein particularly pointed out a very accurately running device which can be readily adjusted for wear is provided, and the envelop is accurately delivered from the surface of the lowered bed without any possibility of being caught under the pusher-arms,

and a smooth face for the folding-bed is still employed.

The details and arrangements herein described may be modified by a skilled mechanician without departing from the scope of my invention as expressed in the claims.

Having thus fully described my invention, what I claim, and desire to secure by Letters Patent, is—

65

65

1. In an envelop-machine, the combination of a vertically-moving folding-bed, means for separating an edge of the envelop from the surface of the bed, and pushers arranged to move across said bed to engage said edge of the envelop and push the envelop off of the bed.

2. In an envelop-machine, the combination of a vertically-moving folding-bed, means for separating an edge of the envelop from the surface of the bed, and notched pushers arranged to move across said bed to engage said edge of the envelop and push the envelop off of the bed.

3. The combination in an envelop-machine, of a vertically-moving folding-bed, separating-pins carried thereby and housed within said bed, and a stop for engaging said separating-pins arranged so that as a bed drops, the lifting-pins will separate an edge of the envelop from the surface of the folding-bed.

4. The combination in an envelop-machine, of a vertically-moving folding-bed, separating-pins housed therein, springs holding the pins in their lowest position, a piece connecting said pins, and a fixed stop for engaging said connecting-piece.

5. The combination in an envelop-machine of the table, a guide-support bolted to the under side of the same and having a dovetailed groove, a slot cut in said guide-support, a folding-bed having a dovetailed tenon engaging said groove, one side of said tenon being cut on an incline, a tapered gib arranged between said inclined side and one side of the dovetailed groove in the support, means for adjusting said gib, a stud secured to said folding-bed and projecting through the slot in said guide-support, and operating connections for said folding-bed engaging said stud.

95

100 In testimony whereof I have hereunto set my hand in the presence of two subscribing witnesses.
